CLAIM

The ornamental design for the fixing device as shown and described.

DESCRIPTION

FIG. 1 is a top, front, and right perspective view of the fixing device according to the present disclosure, where an article embodying the claimed design is shown in broken line; FIG. 2 is a second, top, perspective view of the article of FIG. 1; FIG. 3 is a front view of the article FIG. 1; FIG. 4 is a rear view of the article of FIG. 1; FIG. 5 is a right side view of the article of FIG. 1; FIG. 6 is a left side view of the article of FIG. 1; FIG. 7 is a top view of the article of FIG. 1; FIG. 8 is a bottom view of the article of FIG. 1; and, FIG. 9 is a cross-sectional view of the fixing device of FIG. 1, along line 9-9 of FIG. 7.

The dash-dash broken lines illustrate portions of the fixing device. The dash-dot-dash broken lines illustrate the boundaries of the claimed design. None of the broken lines form part of the claimed design.

1 Claim, 9 Drawing Sheets
